DENTAL PROSTHETIC DEVICE

Wiley J. Adams, Oklahoma City, Okla.

Application March 27, 1957, Serial No. 648,879

4 Claims. (Cl. 32—2)

This invention relates to artificial dentures; and, more particularly, to artificial dentures having improved maxillary and mandibular molar and bicuspid metal teeth.

Artificial dentures, owing to the wide use of such prosthetic devices, have been the subject of intensive study and development for years. Despite the efforts exerted in this field, artificial dentures now in use are only about fifteen percent as efficient as natural teeth. The artificial teeth employed in dentures have been, for the most part, formed of porcelain, though in recent years, teeth formed of acrylic resins have been utilized. Artificial teeth composed of these materials have been incapable of cutting and grinding food to the fine degree that is possible with natural teeth. Numerous attempts have been made to provide artificial teeth composed either entirely of metal or of synthetic resinous or other materials having metallic inserts in the occlusal surfaces. Such artificial teeth relied solely upon the inherent strength of the metal to withstand the pressures exerted by the jaw in use and were not constructed in a manner such that efficient cutting and grinding of food were accomplished. Accordingly, metallic teeth or teeth having metallic elements in the occlusal surfaces thereof have never been adopted commercially.

This invention is based upon the discovery that artificial dentures having metal maxillary and mandibular molars and bicuspids having sharp cusp or cusp-like serrated elements and deep sulci or sulci-like grooves in the occlusal surfaces, and which, when each maxillary bicuspid and molar tooth is completely interdigitated with the corresponding mandibular bicuspid and molar tooth, are highly efficient in cutting and grinding food. The efficiency of the artificial dentures of this invention is attributable to the use of maxillary and mandibular bicuspids and molars having sharp cusp-like members in the occlusal surfaces which are polyhedral in shape and which have sharp apices and sharp edges at the intersection of the inclined surfaces of the polyhedral elements. The bases of these polyhedral cusps are polygonal, having three or more sides, but it is preferred to employ tetrahedral or pentahedral cusp members. In conjunction with the foregoing essential structural features, the bicuspids and molars employed in this invention are characterized by exceptionally deep sulci between the spaced polyhedral elements in the occlusal surfaces. The polyhedral cusp-like members and the sulci therebetween are arranged in rows which extend both laterally (buccal-lingual) and mesially-distally (anterior-posterior). The sharp cusp-like members and exceptionally deep sulci therebetween are provided by employing spaced polyhedral cusp-like members in which each of the inclined surfaces thereof extend upwardly from the horizontal plane of occlusion at an angle of from 20° to 45°; and, preferably, at an angle of from 28° to 35°. When artificial dentures having corresponding metal maxillary and mandibular bicuspids and molars completely interdigitated are occluded or articulated, the food therebetween is cut and sheared into very fine particles by the points and inclined sharp

2

thin edges of the cusps. In addition, the completely interdigital relation between each pair of maxillary and mandibular posterior teeth (bicuspids-molars) produces a flow of comminuted and mashed food through the deep sulci from the teeth when occluded.

It is, therefore, the primary object of this invention to provide an artificial denture containing maxillary and mandibular bicuspids and molars having anterior-posterior and lateral extending rows of metallic, high, sharp polyhedral cusp-like members with correspondingly deep sulci therebetween at the occlusal surfaces of the teeth.

Another object of this invention is to provide an artificial denture having self-cleaning, metal posterior teeth provided with high, sharp polyhedral cusps arranged on the occlusal surfaces of the bicuspids and molars in a manner such that each maxillary molar and bicuspid is completely interdigitated with the corresponding molar and bicuspid when the denture is in its occluded or articulated position.

It is still another object of this invention to provide an artificial denture having metallic maxillary and mandibular bicuspids and molars provided with high, sharp polyhedral cusps and deep sulci therebetween wherein the inclined surfaces of the polyhedral cusps extend upwardly from the occlusal surfaces at an angle of between 20° and 45°, and, preferably, at an angle of between 28° and 35°.

A further object of this invention is to provide an artificial denture having metallic maxillary and mandibular bicuspids and molars provided with polyhedral cusp-like members on the occlusal surfaces wherein the apices of the cusps and the edges formed by the intersections of the inclined surfaces thereof are thin and sharp.

A still further object of the invention is to provide metal maxillary and mandibular bicuspids and molars for artificial dentures wherein the bicuspids and molars have rows of polyhedral cusps adjacent the buccal and lingual faces of the teeth and wherein the lowermost edge of one inclined surface of each cusp starts at the adjacent buccal or lingual ridge and the inclined surface extends upwardly and inwardly away from the buccal or lingual ridges so that the apices of the cusps are spaced from the cheek and tongue of the user.

It is also an object of this invention to provide an artificial denture having metal maxillary and mandibular bicuspids and molars secured in plates of synthetic resinous, vulcanized rubber or similar dental base molding materials and a coating of porcelain or an acrylic resin on the buccal and lingual surfaces of the metallic teeth to reduce the transmission of heat from the teeth to the cheeks of the user; and, especially, to enhance the appearance of the teeth.

The foregoing and other objects are attained by this invention, the preferred embodiments of which are taught in the following description and illustrated in the accompanying drawings wherein:

Figure 1 is an occlusal surface view of the maxillary and mandibular portions of an artificial denture including metallic bicuspids and molars constructed in accordance with the principles of this invention;

Figure 2 is a perspective view of the posterior portions of one side of the maxillary and mandibular dentures from the buccal side with the dentures in occlusive relationship;

Figure 3 is an enlarged fragmentary perspective view of the metal bicuspid and molar teeth in the mandibular denture;

Figure 4 is an enlarged fragmentary perspective view of the metallic bicuspid and molar teeth in the mandibular denture showing more of the occlusal surface and depicting the arrangement of the cusps and sulci in the occlusal surface in detail;

Figure 5 is an occlusal surface view of the maxillary and mandibular portions of an artificial denture including a modification of the metallic bicuspids and molars constructed in accordance with this invention;

Figure 6 is a perspective view of the posterior portions of one side of the maxillary and mandibular dentures shown in Figure 5, from the buccal side with the dentures in occlusive relationship;

Figure 7 is an enlarged fragmentary perspective view of the metal bicuspid and molar teeth in the mandibular denture shown in Figure 5; and

Figure 8 is an enlarged fragmentary perspective view of the metallic bicuspid and molar teeth in the mandibular denture shown in Figure 5 showing more of the occlusal surface and depicting the arrangement of the cusps and sulci in the occlusal surface in detail.

Referring to the drawings, the artificial denture comprising this invention is shown in Figure 1 as being composed of a synthetic resinous or other dental molding material upper plate 1 and a lower or mandibular plate 2 formed of a synthetic resinous material. The synthetic resins commonly used in the dental prosthetic field, such as, for example, the well known acrylic dental molding resins may be used in constructing the plates 1 and 2. The lower plate 2 has two molar teeth 3-3 and two bicuspids 4-4 set in the posterior regions of each side of the plate. The molar and bicuspid teeth 3-3 and 4-4 are composed of metal and may be formed by casting any of the metals of extreme hardness which are non-ferrous, non-corrosive, non-magnetic, stainless and capable of being given a high polish that are commonly used in the dental art. It is preferred to employ metals such as cobalt-chromium alloys containing 90% of cobalt and chromium. One such alloy sold under the trade name "Vitallium" is very desirable. This alloy has the following properties: tensile 100,000-200,000 p.s.i., yield 63,000-67,000 p.s.i., Rockwell hardness C24-38, elongation 2-6% and a modulus of elasticity in tension 30,000,000. Another metal alloy suitable for the purposes of this invention is sold under the trade name "Duralieum" which has properties comparable to "Vitallium." Corresponding pairs of molar teeth 5-5 and bicuspid teeth 6-6 are secured in the upper plate. The maxillary molar and bicuspid teeth 5-5 and 6-6 are similarly formed of a metal such as described above.

The novel feature of this invention resides in the structural features of the maxillary posterior teeth 5-5 and 6-6 and the mandibular posterior teeth 3-3 and 4-4 at their occlusal surfaces. The molars 3-3 are provided with a plurality of polyhedral cusps, preferably three adjacent the buccal side thereof and three adjacent the lingual side of the tooth. In the form of this invention shown in Figures 1-4, inclusive, the novel cusp elements employed are shown as being in tetrahedral form. These tetrahedrally-shaped cusps are tall and each cusp 7 has a sharply pointed apex. There are three inclined flat surfaces on each cusp 7. One inclined surface 8 of each cusp in the row thereof adjacent the buccal surface of the tooth extends upwardly and inwardly away from the buccal ridge of the tooth. There is a corresponding inclined surface 9 on each cusp 7 which is adjacent the lingual side of the tooth and this inclined surface likewise extends upwardly from and inwardly away from the lingual ridge of the tooth. In the foregoing manner the apices of the cusps 7 are spaced inwardly from the buccal and lingual surfaces of the tooth which prevents the sharp points of the cusps 7 from injuring the cheek and the tongue of the user. Each cusp 7 has two inclined surfaces 10 that extend from the apex of the cusp downwardly to the base of the cusp; and, by spacing the cusps 7 from one another deep grooves or sulci 11 are provided in the occlusal surface of each molar tooth 3-3. The sulci 11 are interconnected and each sulci extends in a lateral or in an anterior or posterior direction to a side of the tooth as is apparent from Figure 4.

In order to obtain an efficient cutting and grinding action with the teeth it is essential that the tetrahedral cusps be relatively high and have permanently sharp edged occlusal ridges. The inclined surfaces 8, 9, and 10 of each cusp 7 intersect to form thin sharp cutting ridges 12. The height of the cusps necessary to obtain an efficient cutting and grinding of food is provided by maintaining an angle of inclination of the inclined surfaces 8, 9, and 10 with respect to the horizontal plane of occlusion of from 28° to 35°. While an angle as large as 45° may be used it is not necessary to employ angles of inclination larger than about 35° since the efficiency of the tooth is not substantially increased thereby.

The bicuspid teeth 4-4 in the lower plate are provided with two tetrahedral cusps 13 which are the same in construction and arrangement as the tetrahedral cusps 7. Thus, the cusps 13 have sharp points and each has an inclined surface 14 which extends upwardly from and inwardly away from the buccal or lingual ridge of the tooth adjacent thereto. The cusps 13 also have inclined surfaces 15 which define deep sulci extending to the mesial and distal sides of the tooth. The angle of inclination of the inclined surfaces 14 and 15 of the cusps 13 is between 20° and 45° but an angle of inclination in the range of from 28° to 35° is preferred.

The upper or maxillary plate 1 is constructed in a manner such that the molar teeth 5-5 and the bicuspid teeth 6-6 are each vertically aligned with respective molar teeth 3-3 and bicuspid teeth 4-4 in the lower plate. The maxillary molar teeth 5-5 are constructed in the identical manner as the mandibular molars 3-3 except for the fact that the tetrahedral cusps 16 are offset with respect to the cusps 7. This arrangement permits perfect interdigitation of the cusps 7 and 16 when the artificial denture is occluded as is shown in Figure 2. The position of the inclined surfaces of the cusps 16 and the angle of inclination thereof with respect to the horizontal plane of occlusion are identical to those of the cusps 7 so that the cusps 7 and 16 mesh perfectly. The bicuspids 6-6 of the upper denture each have a pair of tetrahedral cusps 17 which are identical in structure with the cusps 13 of bicuspids 4-4 and are likewise offset with respect to the latter so that a perfect bite may be obtained.

It will be apparent from the foregoing description that the dentures 1 and 2, when subjected to normal usage are capable of both lateral and anterior and posterior excursion or movement. The sharp points or apices of the cusps 7, 13, 16, and 17 will penetrate food with ease under the pressures normally exerted in the mouth. When the dentures are moved toward an occluded position in either a lateral or an anterior-posterior direction the sharp inclined ridges of each cusp formed by the intersection of the several inclined surfaces thereof, efficiently cut the food. In addition, the cusps 16 are moved into an interdigital relationship between the cusps 7 and thus mash the cut food. The latter is due to the action resulting from the movement of the tetrahedral cusp 16 into a complementary space between a pair of cusps 7-7; and, as the wedging inclined surfaces approach, high pressures are brought to bear upon the food particles therebetween. As this movement continues, and the upper and lower dentures approach an occluded position, the food is expressed laterally and in mesial-distal directions through the deep sulci from the teeth.

A modification of the previously described embodiment of this invention is shown in Figures 5 to 8, inclusive. The underlying theory and operation of this modified form of the invention is the same as that of the embodiment thereof shown in Figures 1 to 4, inclusive and the principal structural variation between the two embodiments of the invention is that, in the form shown in Figures 5-8, inclusive, the occlusal surfaces of the teeth are provided with serrations which are cusp-like pentahedral elements. In Figure 5 there is shown a lower plate 18 having secured therein a pair of molars 19-19 and a

pair of bicuspids 20—20 in the posterior region on each side of the plate. The plate 18 is formed of a synthetic resin such as an acrylic molding resin or other suitable dental molding material and the molars 19 and the bicuspids are formed of a suitable metal such as those previously mentioned. Referring to Figure 5, it will be seen that the maxillary molars 19—19 have serrated occlusal surfaces which provide saw-tooth-like points which are obtained by providing a plurality of rows of pentahedral cusp-like elements 21. One such row of elements 21 extends in a mesial-distal direction adjacent the lingual side of each molar 19 and a second row extends in the same direction adjacent the buccal side of the tooth. Intermediate these two rows of cusp-like elements there is a third row of such elements extending in the same mesial-distal direction. The elements 21 in each such row are aligned with the adjacent elements 21 in adjacent rows thereof to provide a plurality of rows extending laterally between the buccal and lingual sides of the molar 19. The cusp-like elements 21 in the rows adjacent the buccal and lingual surfaces of the molar 19 each have an inclined surface 22 which extends upwardly from and inwardly away from the adjacent buccal or lingual ridge of the tooth so that the apex of each element 21 in the outer rows will not injure the cheek and tongue of the user. In the lower plate 20 it is preferred to employ three rows of four elements 21, thus providing a total of twelve pentahedral elements 21. The cusp-like elements 21 are spaced from one another at the bases thereof and the inclined surfaces 23 thereof provide channels or deep grooves which are sulci-like and extend both laterally and in anterior and posterior directions to the sides of the tooth. The angle of inclination of the inclined surfaces 22 and 23 of the elements 21 is between 28° and about 45°; and preferably is about 45° with respect to the horizontal plane of occlusion. The bicuspids 20—21 shown in Figures 5—8 do not differ in structure from the bicuspids 4—4 and 6—6 shown in Figures 1 to 4 of the drawings; but, if desired, may have the occlusal surfaces thereof serrated in the same manner as are the surfaces of the molars 19—19, but a proportionately smaller number of cusp-like elements are formed on the occlusal surface of such bicuspids.

The upper plate 24 which is also formed of a suitable dental molding material has two maxillary molars 25—25 secured therein on each side of the plate in the posterior regions thereof which are aligned with the mandibular molars 19—19 in the lower plate 18. Two bicuspids 26—26 are also secured in each side of the upper plate 24 and are also aligned with the bicuspids 20—20 in the lower plate. The bicuspids 26—26 are shown as being identical with the bicuspids 6—6 shown in Figures 1 to 4, inclusive, but these may have serrated occlusal surfaces as described as being useful in the bicuspids 20—20. The maxillary molars 26—26 which are also formed of a suitable metal such as, for example, "Duralieum" or "Vitallium," as previously described and are provided with a plurality of pentahedral cusp-like elements 27 having sharp pointed apices and inclined flat side surfaces 28 and 29. The inclined surfaces 28 on the outer rows of elements 27 are, like the cusp-like elements 21 on the mandibular molars 19, inclined upwardly from and inwardly from the buccal and lingual ridges adjacent thereto so that the apices of the elements 27 in these rows are spaced inwardly from these side surfaces of the teeth. The cusp-like elements 27 in the upper plate are offset with respect to the elements 21 in the corresponding aligned lower molars 19—19. The offsetting of the elements 27 and 21 in the upper and lower molars, respectively, permits such cusp-like elements to interengage in an interdigital relationship when the upper and lower plates 24 and 18 are occluded. In addition, the use of the same angles of inclination of the inclined surfaces of the cusps 27 and 21, insures a perfect meshing therebetween when these are interdigitated and the upper

and lower plates 24 and 18 are closed in centric relation. The maxillary and mandibular molars 25—25 and 19—19 operate in the same manner that the molars 3—3 and 5—5 shown in Figures 1—4, inclusive, operate. 5 The principal value of the modified form of molars shown in Figures 5 to 8, inclusive, is that teeth of this form are more suitable for use in cases having a condition known as a short or closed bite.

10 The metal teeth, and especially the bicuspid teeth shown in Figures 1—8, inclusive, may be exposed to view during use. In order to enhance the appearance thereof, a facing S of porcelain or an acrylic resin on the buccal surfaces of the bicuspids may be used.

The posterior metallic teeth employed in this invention 15 constitute a distinct departure in structure and theory from those heretofore employed. It has been recognized that the efficiency of a denture depends upon the structure of the posterior teeth used therewith and some attempts have been made to use posterior teeth having 20 pyramidal cusps. However, in the other tooth structures heretofore employed the cusps has been low and the angles of inclination of the inclined surfaces whether flat or arcuate, have been correspondingly low; usually of the order of from 5° to 10° at the most. Cusp or 25 cusp-like members of such a type are, primarily, capable only of grinding food and any cutting action therewith is negligible. Furthermore, posterior teeth have not, heretofore, been arranged so as to provide for complete interdigititation between corresponding upper and lower 30 molars so as to provide complete contact between the interdigitated surfaces of the cusp or cusp-like elements. The molars and bicuspids of this invention are completely 35 interdigititated when occluded and the steep inclined surfaces thereof which provide sharp points at the cusp apex and thin sharp edges not only grind but cut food rapidly. The high, sharp pointed cusps with very thin edged ridges arranged to provide deep sulci cooperate to render 40 artificial dentures more efficient in masticating food than has been possible heretofore. Whereas the efficiency of mastication with artificial dentures heretofore used has been about 15 percent, based on the efficiency of natural teeth, the efficiency of dentures constructed according to this invention is about 50 percent, based on the efficiency of natural teeth.

45 I claim:

1. A dental prosthesis comprising upper and lower dentures having upper and lower metal molar and bicuspid teeth each having a central vertically disposed longitudinal axis, each of said upper molar and bicuspid teeth having its central vertically disposed longitudinal axis fully aligned with the central vertically disposed longitudinal axis of each corresponding lower molar and bicuspid tooth when said upper and lower dentures are in a normal occluded relation to provide full contact 55 between the entire area of the opposing surfaces of each opposing pair of corresponding upper and lower molar and bicuspid teeth, said upper and lower molar and bicuspid teeth each having a plurality of spaced rows of polyhedral cusp members on the occlusal surfaces thereof, said cusp members having sharp apices and a plurality of inclined flat side surfaces providing thin sharp inclined ridges and defining deep lateral and anterior-posterior grooves therebetween extending to the sides of the teeth, said inclined surfaces each having an angle of 60 inclination with respect to the horizontal plane of occlusion in the range of from 28° to about 45° the apices of the cusps of each upper molar and bicuspid tooth being offset with respect to the apices of the cusps of the corresponding opposing lower molar and bicuspid teeth to provide complete interdigititation between the apices of each aligned pair of teeth of corresponding upper and lower molar and bicuspid teeth when said upper and lower dentures are in a normal occluded relation.

70 2. A dental prosthesis as set forth in claim 1 wherein 75 said upper and lower molar and bicuspid teeth polyhedral

cusp members are tetrahedral and said inclined surfaces have an angle of inclination with respect to the horizontal plane of occlusion of between 28° and 35°.

3. A dental prosthesis as set forth in claim 1 wherein said upper and lower bicuspid teeth have a non-metallic facing on the buccal surfaces thereof.

4. A dental prosthesis as set forth in claim 1 wherein said upper and lower molar and bicuspid teeth polyhedral

cusp members are pentahedral and said inclined surfaces have an angle of inclination with respect to the horizontal plane of occlusion of between 28° and 35°.
